UNITED STATES PATENT OFFICE.

HARRY W. CHITTENDEN, OF MOORLAND, IOWA.

TRAFFIC SIGNAL.

Application filed August 26, 1922. Serial No. 584,545.

To all whom it may concern:

Be it known that I, HARRY W. CHITTENDEN, citizen of the United States, residing at Moorland, in the county of Webster and 5 State of Iowa, have invented certain new and useful Improvements in Traffic Signals, of which the following is a specification.

This invention relates to an improved traffic signal and seeks, as one of its principal objects to provide a device of this character which will be traffic actuated for automatically controlling movement of traffic in opposite directions at the intersection of streets or the like.

15 The invention has as a further object to provide a device which will display clear signals to traffic traveling upon one street and stop signals to cross traffic traveling upon an intersecting street until a certain 20 number of vehicles have passed the device, when the device will be actuated to display clear signals to the cross traffic and stop signals to said first mentioned traffic and vice versa.

25 And the invention has as a still further object to provide a device which will be characterized by structural simplicity, which may be readily installed, and which will be equipped to display signals at night 30 as well as in the day time.

Other and incidental objects will appear hereinafter.

In the drawings:

35 Figure 1 is a perspective view of my improved signal.

Figure 2 is a vertical fragmentary sectional view through the device.

40 Figure 3 is a horizontal sectional view on the line 3—3 of Figure 2, looking in the direction of the arrows.

Figure 4 is a detail sectional view on the line 4—4 of Figure 3, looking in the direction of the arrows.

45 Figure 5 is a detail sectional view on the line 5—5 of Figure 3, looking in the direction of the arrows, and

Figure 6 is a detail perspective view particularly showing the counter-weight employed.

50 In carrying the invention into effect, I employ a base member 10 upon which is erected a tower 11 and leading from the tower at the upper face of the base is a channel 12 entering a recess 13 at one end 55 of the base. Formed through the base at said recess is an opening 14 and normally

closing said recess as well as the channel 12 is a cover plate 15. As shown in Figure 1, the power is preferably provided at one side thereof with a door 16 and journaled through the base to extend axially through the tower is a vertical shaft 17 to the upper end of which is fixed a signaling member or disc 18 carrying a depending rim 19. This rim is provided at diametric points with red colored stop signals 20 and at right angles to said signals with green colored clear signals 21. Suitably imposed upon the rim in each of the spaces between said signals are the numbers 1, 2 and 3 70 equally spaced from each other as well as from adjacent signals. Fixed upon the shaft within the upper end of the tower is a second signaling member or disc 22 mounting diametrically disposed red colored stop signal lamps 23 as well as diametrically disposed green colored clear signal lamps 24 arranged in a plane at right angles to the lamps 23. Current may be supplied to these lamps in any suitable manner and formed in corresponding side walls of the tower at the upper end thereof are oppositely disposed windows 25 while opposite corresponding side walls of the tower are provided with similar oppositely disposed windows 26. Preferably, arrows or other suitable pointers 27 are provided upon the side walls of the tower pointing toward said windows.

75 Fixed to the lower end portion of the shaft 17 is a ratchet 28 and straddling said ratchet is a yoke 29 swingingly mounted upon the shaft. Pivoted upon said yoke to coact with the ratchet is a pawl 30 supported by a pin 31 extending between the arms of the yoke and secured to the yoke to engage said pawl is a spring 32 holding the pawl in engagement with the ratchet. Rising from the base 10 adjacent the shaft is a bracket 33 and pivoted upon said bracket is a pawl 34 held by a spring 35 to engage the ratchet, locking the ratchet against counter-rotation, the spring being secured at one end to the bracket 33 and bearing at its opposite end against the free end of said pawl.

80 Pivoted upon the base to project at one end within the opening 14 of the base is a rock lever 36, the base being provided with a recess 37 to receive the opposite end of said lever lying flush with the base. Supporting said lever is a pivot pin 38. Pivoted at one end within the recess 13 is an arm 39

and secured to the lower side of the base at the opening 14 is a casing 40 between the side walls of which extend spaced transverse cross pins 41 journaling pulleys 42 and 43. Connected at one end to the yoke 29 is a cable or other suitable flexible element 44 freely received within the channel 12 of the base and secured at its opposite end to the free end of the arm 39. This cable is trained around a pulley 45 within the tower 11 and extending between the free end of the arm 39 and the inner end of the rock lever 36 is a second cable 46 which is trained over the pulley 42 and beneath the pulley 43, it being observed in this connection, as shown in Figures 4 and 5, that the pulley 43 lies in a plane medially of the lever and is spaced below the pulley 42. Thus, as will be seen, when the outer end of the lever is depressed, the arm 39 will be swung for rocking the yoke 29 to rotate the shaft 17 and connected to said yoke at its rear side is a spring 47 for retracting the yoke and elevating the forward end of the lever when said lever is released. Extending transversely within the tower 11 is a shaft 48 upon which is journaled a pulley 49 and trained over said pulley is a cable 50 attached at one end to the cable 44 within the tower while to the opposite end of the cable 50 is secured a counter-weight 51. As will be perceived, this counter-weight will act auxiliary to the spring 47 for elevating the forward end of the rock lever 36 and maintaining the cables 44 and 46 taut, and preferably, a staple 52 is arranged to straddle the cable 44 at a suitable point in advance of the pulley 45 to prevent the cable 44 from being lifted or pulled out of engagement with said pulley. Mounted upon the base adjacent the lever 36 is a guard member 53 inclined laterally with respect to the lever in the rear of the pivotal mounting thereof.

Referring now more particularly to Figures 1 and 2 of the drawings, it will, for convenience, be assumed that the signaling member 18 is set to display the stop signals 20 to east and west traffic so that the clear signals 21 are displayed to north and south traffic. Accordingly, east and west traffic will be stopped and as vehicles traveling north and south pass over the lever 36, depressing the lever, the signaling member 18 will, as will be at once understood in view of the preceding description, be rotated step by step. Upon the passage of the first vehicle the numerals 1 upon the signaling member will be brought opposite the arrows 27. Similarly, upon the passage of the second vehicle, the numerals 2 will be brought opposite said arrows, and so on until four vehicles have passed, when the stop signals 20 will be displayed to north and south traffic while the clear signals 21 will be displayed to east and west traffic. Thus, north and

south traffic will be held up until four vehicles traveling east and west have passed the device when the device will register clear signals to north and south traffic. I accordingly provide a traffic operated signal which will function to regulate the movement of traffic at intersecting streets. At night, the lamps 23 and 24 will be energized so that when the lamps 23 display clear signals at the windows 25, north and south traffic, for instance, will be permitted, while east and west traffic will be stopped by the stop signals displayed by the lamps 24 at the windows 26. Then, as the signaling member 18 is turned, stop signals will be displayed at the windows 25 while clear signals will be displayed at the windows 26.

Upstanding from the base 10 in front of the yoke 29 is, as best shown in Fig. 3, a post 54 and pivoted upon said post is a detent 55 the forward end of which is disposed to engage the ratchet while the rear end of said detent is disposed in the path of swinging movement of said yoke. Consequently when the yoke is swung forwardly for rotating the signaling member 18, the yoke will rock the detent into engagement with the ratchet for preventing a possible over rotation of the shaft at each actuation of the lever 36.

Having thus described the invention, what is claimed as new is:

1. A traffic signal including a rotatable signaling member having spaced clear and stop signals thereon, traffic actuated means for rotating said member to interchange the positions of said signals with respect to the traffic, and means for limiting the rotation of said member at each actuation thereof.
2. A traffic signal including a rotatable signaling member having spaced clear and stop signals thereon, traffic actuated means for rotating said member step by step to interchange the positions of said signals with respect to the traffic, and means for limiting the rotation of said member at each step.
3. A traffic signal including a rotatable signaling member having spaced clear and stop signals thereon, traffic actuated means for rotating said member step by step, and means upon the member for registering the position thereof at each step.
4. A traffic signal including a rotatable shaft, a signaling member carried thereby and provided with spaced clear and stop signals, traffic actuated means for rotating said shaft to interchange the positions of said signals with respect to the traffic and including ratchet mechanism associated with the shaft, and means operable by said mechanism for limiting the rotation of said shaft at each actuation thereof.
5. A traffic signal including a rotatable shaft, a signaling member carried thereby

and provided with spaced clear and stop signals, ratchet mechanism for turning the shaft, a traffic actuated lever operatively connected with said mechanism, and means for limiting the rotation of said shaft at each actuation thereof.

6. A traffic signal including a rotatable shaft, a signaling member carried thereby and provided with spaced clear and stop signals, a ratchet fixed to the shaft, a yoke swingingly mounted upon the shaft straddling said ratchet, a pawl carried by said yoke to coact with the ratchet, and a traffic actuated member for swinging said yoke and rotating the shaft to interchange the positions of said signals with respect to the traffic.

7. A traffic signal including a rotatable shaft, a signaling member carried thereby and provided with spaced clear and stop signals, a ratchet fixed to the shaft, a yoke swingingly mounted upon the shaft straddling the ratchet, a pawl mounted upon the yoke to coact with the ratchet, a cable connected to said yoke, a traffic actuated lever connected with the cable and operable for swinging said yoke to rotate the shaft and interchange the positions of said signals with respect to the traffic, means for re-

tracting the yoke when swung, and a counter-weight connected with said cable for maintaining the cable taut. 20

8. A traffic signal including a base, a tower rising therefrom, a rotatable shaft projecting at the upper end of the tower, 35 a signaling member fixed upon the upper end portion of said shaft and having spaced stop and clear signals, a traffic actuated rock lever pivoted upon the base and operatively connected with said shaft for rotating the 40 shaft to interchange the positions of said signals with respect to the traffic, and means for limiting the rotation of said shaft at each actuation thereof.

9. A traffic signal including a rotatable 45 shaft, a signaling member carried thereby and provided with spaced clear and stop signals, a ratchet fixed to the shaft, a yoke swingingly mounted upon the shaft, a pawl carried by said yoke to coact with the ratchet, 50 a traffic actuated member for swinging said yoke and rotating the shaft to interchange the positions of said signals with respect to the traffic, and a pivoted lever movable by the yoke to engage the ratchet limiting the 55 shaft against rotation.

In testimony whereof I affix my signature.
HARRY W. CHITTENDEN [L. s.]
